UNITED STATES PATENT OFFICE.

HEINRICH WILLEM KAREL DE BREY, OF THE HAGUE, NETHERLANDS.

SOUND DAMPER.

Application filed June 18, 1924. Serial No. 720,859.

The object of my invention is to provide improved means for absorbing or eliminating accidental or parasitic sound and thereby increase the tonal clarity in the transmission or amplification of reproduced sound through amplifying horns, tone arms, sound chambers as used in connection with the so-called hornless type of cabinet gramophones, loud talkers and any other more or less tubular transmitting elements suitable for this purpose, irrespective of whether the sound is reproduced by mechanical, electrical or other instrumentalities.

The accidental or parasitic sound may originate from the proper vibrations of a diaphragm or other sound transmitting parts, from the scratching of the stylus needle or diamond over the record of talking machines or from other sources, but whatever its source may be, its wave lengths are, as a rule, appreciably different from those of the sound which it is desired to convey, and I have now discovered that owing to said difference in wave lengths it is possible to remedy the said defect in a very simple manner by separating the disturbing frequencies from the others and absorbing them more or less fully. This result is obtained by the provision, within the horn or other more or less tubular sound transmitting element, of a member, or a plurality of members for "breaking" the undesired sound waves, said member being so arranged and constructed as to check or hamper and also absorb or muffle the undesired vibrations while allowing the other frequencies to pass on.

An essential feature of my novel sound improver is, that it clears the central portion of the horn or the like, as contradistinguished from known means such as a ball like member disposed centrally within the horn at an adjustable distance from the neck and serving only for controlling the intensity of the sound, another important feature of my invention being that the sound improver is in perfect contact with the inner wall of the horn or the like through only part of the circumference thereof. In practice it has been found that very satisfactory results are obtained by the employment of a sound improver which extends through one half to three quarters of the interior circumference of the horn, leaving the balance unobstructed.

My novel sound improver is made of a

suitable sound damping material such as rubber, felt, fabric, etc., and is so formed that the undesired sound waves, which are propagated along that portion of the wall of the sound transmitting element where the sound improver is placed, cannot continue their paths over the improver, or between the latter and the wall, but are actually checked. For this purpose the front face of the absorber may be concave, or convex, or have another suitable form.

In order that my novel sound improver may be in perfect contact with the inner wall of the horn, it may be pasted thereto, or sunk thereinto, or held in place in any other suitable manner at the required distance from the mouth, said distance depending, inter alia, upon the construction of the horn or the like and the character of the sound to be conveyed. Preferably, however, I use a loose improver adapted by its own resiliency, or by the resiliency of a spring, to be firmly pressed against the inner wall of the horn, as this has the advantage that I can determine where the improver should be located to have the best effect in the reproduction of a given record or the amplification of a given voice. As a rule it will be found that with a gramophone horn of conventional configuration the best results are obtained when the improver is placed in the neck or the portion contiguous therewith.

The annexed drawing illustrates, by way of example only, a sound improver in accordance with my invention, Fig. 1 being a longitudinal section, and Fig. 2 a cross section on a reduced scale of the improver fitted in the neck of a sound amplifying horn of conventional form.

The improver shown in Fig. 1 simply consists of a spring blade 3, wrapped around the central portion of which is a rope of flannel 4 forming a pad of sound absorbing material, and the ends of the blade 3 are bent into hooks 5 as shown. It will be understood that, when I force the ends of the spring blade towards one another between my fingers I can introduce the improver into an amplifying horn 6 and put it into place and that, when I release the spring, the pad 4 is firmly pressed against the inner wall through part of the circumference of the horn, thereby positively checking the undesired sound waves. If necessary, I can then simply push the improver further inward or outward as circumstances require, and

thus cause the improver to occupy a greater or a smaller portion of the inner circumference of the horn.

What I claim is:—

- 5 1. In combination with a sound transmitting element, of means arranged in said element and in contact with the inner surface of the wall thereof throughout substantially its full length, said means having a length
10 approximating one-half the cylindrical length of the wall at the point of application of the means and extending inwardly from the inner surface of said wall to provide throughout its length a complete interruption to the passage of sound waves.
- 15 2. In combination with a tubular sound transmitting element of a dampening member in solid form adapted to be held in contact with the inner surface of the element
20 throughout substantially its full length and extending substantially one-half the cylindrical length of such wall at the point of application, said dampening member interposing a direct barrier to the passage of
25 sound waves throughout its length and thickness.
- 30 3. In combination with a tubular sound transmitting element, of a solid substantially cylindrical dampening member engaging the inner surface of the element and extending throughout approximately one-half the cylindrical length of the wall at the point of application, said dampening mem-

ber being of a thickness radially of the member less than the radius of such member, 35
whereby to interpose a solid barrier to the sound waves throughout an area having a circumferential length approximately one-half the circular length of the element and a thickness less than the radius of the element, the central portion of the element and the remaining area of the wall surface thereof being completely unobstructed.

4. A dampening barrier for sound waves 40
passing through a tubular transmitting element, comprising a substantially cylindrical member constructed solidly of dampening material and having a length approximating one-half the cylindrical length of the element at the point at which said member is 45
to be placed, the thickness of the member being less than the radius of the element at the point of application of the member.

5. The combination with a tubular sound 50
transmitting element, of a dampening member of solid formation having a length approximately equal to one-half the circumferential length of the element at the point of application of the member, and means 55
carried by the member for resiliently holding the same in contact with the inner surface of the element at the point of application.

In testimony whereof I affix my signature.

HEINRICH WILLEM KAREL de BREY
